Arthur H. Adams.

UNITED STATES PATENT OFFICE.

ARTHUR H. ADAMS, OF SPARKILL, NEW YORK, ASSIGNOR TO WESTERN ELECTRIC COMPANY, OF NEW YORK, N. Y., A CORPORATION OF ILLINOIS.

RETRACTOR FOR PRINTING TELEGRAPHHS.

1,098,545.

Specification of Letters Patent. Patented June 2, 1914.

Application filed February 12, 1912. Serial No. 677,622.

To all whom it may concern:

Be it known that I, ARTHUR H. ADAMS, citizen of the United States, residing at Sparkill, in the county of Rockland and State of New York, have invented a certain new and useful Improvement in Retractors for Printing-Telegraphs, of which the following is a full, clear, concise, and exact description.

10 This invention relates to printing telegraphs, and devices of like character in which the type are carried upon a revolving drum.

More particularly, its object is to provide 15 a means whereby the printing of the same letter any number of times in succession cannot be accomplished without the type for that particular letter being inked previous to each time it is used on account of the shaft 20 making approximately a complete revolution.

In the drawings—Figure 1 is a perspective view of the apparatus used to accomplish the above object; Figs. 2, 3, 4 and 5 show in detail 25 various stages in the operation of the device; and Fig. 6 shows a type magnet with its armature and the engaging arm on the type drum spindle.

In Fig. 1, the starting magnet 13 and the 30 retractor magnet 12 are mounted upon the circular frame 22, the center portion of which frame is cut away to form a circular opening through which passes the type drum spindle 14. The type magnets 10 are shown 35 mounted upon the circular L-shaped member 23, the armatures 11 of these magnets being mounted upon the outer upturned edge 24 of the circular plate 25. The inner ends 19, 20, 21, etc., of said armatures pass 40 through slots in the inner upturned edge 29 of said plate 25 and when in normal position rest upon the lower offset portion 26 of said inner edge.

The shaft 14 tends to revolve in a counter-clockwise direction and is operated by a 45 spring or other suitable motor. Upon the shaft 14 is mounted the type drum (not shown), the ratchet 15 and the arm 18. The pawl 16 engages the ratchet 15 and is operated by the armature 27 of the starting 50 magnet 13. Also the pawl 17 engages the wheel 15 and is operated by the armature 28 of the retractor magnet 12. The inner ends 19, 20, 21, etc., of the armatures 11 when 55 in their upper position engage the arm 18

and by so doing stop the shaft 14 in a definite position depending upon which one of the type magnet armatures is operated.

Assume that the inner end 20 of an armature has been raised, as shown by the dotted lines in Fig. 6, by a current sent through the corresponding type magnet 10 and is now in the path of the revolving arm 18. A circuit is next closed which operates the starting magnet 13, withdrawing the pawl 16 as 65 shown by the dotted lines. The shaft 14 is now free to revolve and by means of a spring or other suitable mechanism revolves in a counter-clockwise direction until the arm 18 comes in contact with the armature end 20 70 which stops the shaft 14 as shown in Fig. 3. At this point the type on the type drum corresponding to the key pressed is in its printing position. Assuming the printing operation to be completed, a circuit is then 75 closed through the retractor magnet 12 which causes the pawl 17 to engage the wheel 15 and rotate the shaft 14 in a clockwise direction. In Fig. 4 it will be seen that the amount of this rotation is less than the 80 length of a tooth measured on the circumference of the wheel 15, hence the clockwise rotation causes the pawl 16 to ride up on a tooth as shown in Fig. 4. This rotation by means of the retractor magnet also separates 85 the arm 18 and the armature end 20. The type magnet 10 being demagnetized the armature is permitted to drop into its normal position as shown in Fig. 6. The circuit through the retractor magnet is now 90 opened and the shaft 14 revolves in its normal clockwise direction for a short distance until the pawl 16 has reached the root of the tooth upon which it was riding. This condition is shown in Fig. 5. It will be further noticed in Fig. 5 that the arm 18 has 95 gone beyond the armature end 20 so that if it is desired to print the letter corresponding to the key operating the armature end 20 immediately following the first use of 100 that letter, i. e., several times in succession, it is necessary for the shaft 14 to make a complete revolution. This brings the type into contact with the inking device each time before it is used, thereby preventing the type 105 being used when uninked and insuring the legible printing of the characters.

What I claim is:

1. In a device of the character described, a shaft normally tending to rotate, means 110

- for preventing the rotation of said shaft, release means therefor, stops for arresting said shaft in any position, and means operable to rotate the shaft in a direction contrary to its normal direction of rotation.
2. In a device of the character described, a rotatable shaft, holding means for preventing rotation of the shaft, means for releasing the holding means, retractive means for rotating the shaft in a direction contrary to its normal direction of rotation, selective means for stopping the shaft at any desired point, the selective means released by the retractive means, the holding means stopping the shaft beyond the point at which the shaft was stopped by the selective means, whereby the shaft makes a complete or nearly complete revolution before it can be stopped again at the same point by the selective means.
3. In a device of the character described, a rotatable shaft, a ratchet and an arm attached thereto, a holding pawl engaging said ratchet for preventing rotation of the shaft, an electromagnet for releasing the pawl, an electromagnetically operated retractive pawl engaging said ratchet for rotating the shaft in a direction contrary to the normal direction of rotation of the shaft, a plurality of armature levers adapted to engage the arm for selectively stopping the shaft at any desired point, the armatures released by the action of the retracting pawl, the holding pawl stopping the shaft beyond the point at which the shaft was stopped by a raised armature end, whereby the shaft makes a complete or nearly complete revolution before it can be stopped again at the same point by the selective means.
4. In a device of the character described, a rotatable shaft, a ratchet and a radial arm attached thereto, a holding pawl normally engaging said ratchet, an electromagnet for operating said pawl to release the shaft, a retractor device consisting of an electromagnetically operated pawl normally disengaged from the ratchet but when operated rotating the ratchet and the shaft in a direction opposite the normal direction of rotation of said shaft, a plurality of armature bars radially disposed to the shaft, their inner ends adapted to be raised, independent means for raising the inner ends of said armature bars into the path of the radial arm, the shaft free to rotate when released until stopped by the radial arm coming into contact with a raised armature end, the armature end released and allowed to drop into its normal position by the action of the retractor device, the holding pawl permitting the shaft to rotate into normal direction sufficiently for the radial arm to pass beyond the now normal armature, whereby the shaft makes a complete or nearly complete revolution before it can be stopped again by the same armature.

In witness whereof, I, hereunto subscribe my name this ninth day of Feb. A. D. 1912.

ARTHUR H. ADAMS.
